DESIGN FOR A BUCKLE

John J. Walsh, Maplewood, Mo., assignor to Milius Shoe Company, St. Louis, Mo., a corporation of Missouri

Application November 1, 1935, Serial No. 59,308

Term of patent 3½ years

To all whom it may concern:

Be it known that I, John J. Walsh, a citizen of the United States residing in the city of Maplewood, county of St. Louis, State of Missouri, have invented a new, original, and ornamental Design for a Buckle, of which the following is a specification, reference being had to the accompanying drawing, forming part thereof.

In the drawing, Fig. 1 is a plan view of a buckle showing my new design; and Fig. 2 is a side view of the same.

I claim:

The ornamental design for a buckle, substantially as shown.
